UNITED STATES PATENT OFFICE.

ERWIN M. COOPER, OF SAN FRANCISCO, CALIFORNIA.

ATTACHMENT FOR TYPEWRITERS.

Application filed December 30, 1922. Serial No. 609,980.

To all whom it may concern:

Be it known that I, ERWIN M. COOPER, a citizen of the United States, and a resident of the city and county of San Francisco, State of California, have invented an Improvement in Attachments for Typewriters, of which the following is a specification.

This invention relates to an attachment for typewriters, and particularly to an attachment by means of which the spacer bar of a typewriter may be operated.

It is an object of the invention to provide an attachment which will relieve the operator of the necessity for using the unnatural downward movement of the hand in actuating the spacer bar, and will make it possible for the operator to actuate the spacer bar by a simple lateral movement of the thumb.

A further object of the invention resides in the provision of a device which is so constructed that it may be easily mounted on any of the commercial typewriters, and that it will be inexpensive to manufacture.

With these and other objects in view, which will become apparent as my description progresses, the invention comprises the combination and arrangement of parts as set forth in, and falling within the scope of, the appended claims.

In the drawings which illustrate one embodiment of my invention—

Figure 1 is a perspective view of the device showing the same clamped on the front bar of a typewriter, and showing its relation to the spacer bar;

Figure 2 is a vertical sectional view;

Figure 3 is a side elevation; and

Figure 4 is a view of the blank from which the operating lever is formed.

The embodiment of the invention which is chosen for the purpose of illustration includes a clamp 10, which is preferably of inverted U-shape in cross section and formed of sheet metal. This clamp is adapted to be mounted on and embrace the front bar 11 of a typewriter and to be held in such position by the screws 12 which pass loosely through one of the legs of the clamp and have screw-threaded engagement with the other leg. Upon the tightening of the screws it will be seen that the two legs of the clamp are drawn toward each other, thus tightly engaging the clamp with the typewriter front bar.

A lever 13 is pivoted at 14, preferably on the leg of the clamp which is adapted to be

located on the inner side of the front bar. This lever in its preferred form is formed from a single piece of sheet metal and is of the third class. One arm 15 of the lever, into which the pivot passes, extends upwardly along the inner leg of the clamp and to a point considerably above the latter. The other arm 16 of the lever extends in an angular relation to the first arm and is provided on its outer or free end with depending ears 17 between which a roller 18 is located, the roller being mounted on a pin 19, which projects between and is mounted in the ears, and depending slightly below the lower edges of the same. This roller is adapted to engage the spacer bar of the typewriter.

It will be noted that the arm 16 is itself of angular form having a portion 20 extending inwardly over the spacer bar and having the roller-carrying portion extending along the spacer bar. The portion 20 of this arm 16 not only is for the purpose of bringing the spacer bar engaging roller into the proper position, but it also accommodates the operating key 21.

The movement of the lever in both directions is limited by a finger 22, which extends from the arm 15 of the lever and operates in a limiting slot 23. In the form of device illustrated in the drawings, this finger projects from the lever to the opposite side of the pivot from which the arm 15 projects and it operates in a slot 23 which is formed in the lower edge of the inner leg of the clamp.

The clamp is placed on the front bar of the type writer and secured in place with the lever disposed between the clamp and the spacer bar, and the arm 16, together with the roller 18 which it carries, overlying the spacer bar, the roller being held in engagement with the upper face of the spacer bar by its weight and the weight of the lever.

In operation, when it is desired to space, it is only necessary for the operator to move the thumb laterally into engagement with the key 21. The force applied to this key will move the lever 13 about its pivot and, through the roller 18, force the spacer bar of the typewriter downwardly.

When the pressure is relieved from the operating key, the spacer bar in its upward movement will return the lever to its initial position.

The finger 22, operating in the slot, limits the downward movement of the lever so that the spacer bar is only forced downwardly to a sufficient distance to produce the desired 5 operation, irrespective of the amount of force applied to the operating key 21, so that the typewriter mechanism is relieved of the undue strain incident to the too forcible depression of the spacer bar. Furthermore, the finger limits the movement of the lever in the opposite direction under the influence of the spacer bar in its rising movement, so that the roller is maintained in operative relation to the spacer bar and 10 the lever is not completely thrown over out of position.

It will be seen that the device is formed of relatively few parts and that the main parts preferably are made of sheet metal 15 which may be produced by a simple stamping operation.

While I have illustrated a particular embodiment, it is, as hereinbefore stated, selected for the purpose of illustration, and I 20 do not wish to be limited to the details of construction, as it is obvious that many changes in the details may be made within the scope of the claims.

What I claim is:

- 80 1. The combination with the frame and spacer bar of a typewriter, of an attachment for operating the spacer bar, comprising a clamp removably mounted on the frame; a lever having one arm pivoted on said clamp and having the other arm extending from the first-mentioned arm and arranged to operate the spacer bar; and an operating key mounted at the junction between said arms.
- 40 2. The combination with the frame and spacer bar of a typewriter, of an attachment for operating the spacer bar, comprising a clamp removably mounted on the frame; a lever having one arm pivoted on said clamp and having the other arm extending from the first-mentioned arm and arranged over the spacer bar; and means formed in said clamp member for limiting the movements of the lever in both directions.
- 50 3. The combination with the frame and spacer bar of a typewriter, of an attachment for operating the spacer bar, comprising a clamp removably mounted on the frame; a lever having one arm pivoted on said clamp and having the other arm extending from the first-mentioned arm and arranged over the spacer bar; an operating key mounted at the junction between said arms; and means formed in said clamp member for limiting the movements of the lever in both directions.
- 60 4. An attachment for typewriters, comprising a clamp adapted to removably engage the front bar of a typewriter; a lever

pivoted on said clamp and having an arm 65 adapted to engage the spacer bar of the typewriter; and cooperating means on the clamp and lever for limiting the movement of the latter.

5. An attachment for typewriters, comprising a clamp adapted to removably engage the front bar of a typewriter; and an angular lever of the third class pivoted on the said clamp, said clamp having an arcuate shaped slot and said lever having a lug 75 working in said slot for limiting the movements of the lever in both directions.

6. An attachment for typewriters, comprising a clamp adapted to removably engage the front bar of a typewriter; a lever 80 having one arm pivoted on said clamp, said lever comprising a single piece of flat metal having one arm extending in angular relation to the other; a pair of ears depending from the arm remote from the pivot; and 85 a roller mounted on a pin extending between said ears.

7. An attachment for typewriters comprising a clamp adapted to removably engage a typewriter frame; an angular lever 90 pivoted adjacent one end of one of its arms to said clamp, the other of said arms having a portion extending in angular relation to the first arm and a portion extending in angular relation to the aforementioned portion; a roller mounted on the free end of the last-mentioned portion of the second arm; and an operating key mounted on the first-mentioned portion of the second arm of the lever.

8. An attachment for typewriters, comprising a clamp adapted to removably engage a typewriter frame, and an angular lever pivoted adjacent one end of one of its arms to said clamp, the other arms comprising a section formed at an angle to the first named arm and transversely overlying the spacer bar of the typewriter, and a section formed at an angle to the transversely overlying section and horizontally overlying 100 said spacer bar.

9. An attachment for typewriters, comprising a clamp; a lever pivoted to the clamp, said lever having an upwardly extending arm, and an arm extending substantially horizontally, said last-mentioned arm having a portion extending in angular relation to the first-mentioned arm, and a portion extending in angular relation to the first-mentioned portion; means on the end of the second arm for engaging the spacer bar of a typewriter; and means for limiting the movements of the lever in both directions.

In testimony whereof, I have signed my 125 name to this specification.

ERWIN M. COOPER.
